CONTROL FOR CLAMPS

Donald H. Cravener, Jr., Chicago, Ill., assignor
to Borg-Warner Corporation, Chicago, Ill., a
corporation of Illinois

Application December 1, 1941, Serial No. 421,186

11 Claims. (Cl. 80—19)

This invention relates to clamping devices for holding a blank to be worked against a rotatable form, and particularly to a means for controlling the operation of the clamps.

In a copending application of Berg, Serial No. 421,613 filed December 4, 1941, there is described a clamping device for holding a circular blank against a rotatable form to permit the central portion of the blank to be rolled radially inwardly by a combination rolling and spinning tool. The clamping device described in the said Berg application comprises a plurality of fingers equidistantly spaced about the periphery of the blank and operated by centrifugal force-responsive means. The clamping device is such that the clamping action increases with the centrifugal force, and enough clamping action is developed to resist any radial inward movement of the blank which might result from the radial inward movement of the spinning and rolling tool.

It is contemplated in the above-mentioned Berg apparatus that the blank will be rolled while hot and that the blank will be rotated at approximately 1200 R. P. M. Obviously, under such conditions, the blank must be completely under control at all times and particularly when it is rotating. A centrifugal clamp, however, is not ordinarily effective unless a predetermined minimum amount of centrifugal force is developed in it, and this minimum force is not developed except above a predetermined speed of rotation of the clamp. This means that below the predetermined effective speeds the clamp is unable to hold the blank on the form and consequently during such time that the blank is rotating below the aforesaid effective speed it may accidentally leave the form and seriously injure the operator.

The principal object of this invention is to provide an improved centrifugal clamp for a rotatable blank wherein said clamp is effective to prevent the blank from leaving a rotatable form whether or not the form is rotating.

Another object of this invention is to provide an improved centrifugal force-responsive clamp for a rotatable blank, which clamp is effective to hold a blank on a spinning form when the form is not rotating, with means under the control of the operator for releasing the clamp when it is desired to remove the blank from the form.

Another object of this invention is to provide an improved centrifugal clamp for a rotatable blank with means under the control of the operator to release the clamp and raise the blank from the supporting platen so that the blank may be gripped by a pair of tongs or otherwise.

A still further object of this invention is to provide a clamp for a blank which is to be rolled against a spinning form wherein the clamp may be operated by centrifugal force, by gravity and also by an external control.

These and other objects and features of this invention will become apparent from the following detailed description when taken together with the accompanying drawings in which:

Fig. 1 is a fragmentary front elevation partly in section of a rolling machine to which the novel clamp means may be adapted.

Fig. 2 is a fragmentary plan view partly in section of the spinning form, the plan view being taken along lines 2—2 of Fig. 1; and

Fig. 3 is an enlarged fragmentary section through the spinning form showing the clamp in released position.

Referring now to the drawings for a detailed description of the invention, the machine illustrated is comprised of a platform 10 which is adapted to be rotated by any suitable means such as a pulley 30 and a rope drive 31 from a prime mover (not shown). A platen 11 is mounted on platform 10 and is provided with a central shaft 12 which is slidably retained in rotatable platform 10. A friction clutch connection 13 is provided between platform 10 and platen 11 whereby to drive the latter from the former. Said platen 11 may be raised or lowered relative to platform 10 by any suitable means, such for example as a lever 14 riding on a cam 15 and operated by an external control 16 which may be in the form of a piston and cylinder. Obviously, any other suitable means for raising and lowering platen 11 may be substituted for the lever and control disclosed.

A frame 17 straddles platen 11 and supports a crank shaft and a connecting rod (not shown) which are used to raise and lower a slide 20. The details of the crank shaft and connecting rod are disclosed in a copending application of A. Doderer, filed November 15, 1941, Serial No. 419,280 and hence will not be described herein.

Said slide 20 supports a roll carriage 21 in which is rotatably mounted a roll 22 for operating against or upon a blank 23 which may be mounted upon platen 11. Said carriage 21 is bolted to a plate 24 which is slidably supported from slide 20 by means of gib 25 extending across said slide 20. Plate 24 is adapted to be moved over the surface of platen 11 by means of a piston rod 26 connected to plate 24 and driven from a cylinder 27 through a piston (not shown) located therein and controlled by suitable fluid under pressure

The details of the cylinder are not a part of this invention and accordingly likewise are not described in detail herein.

Downward movement of slide 20 is limited by stop blocks 28 formed in frame 17, said blocks contacting adjustable blocks 29 in slide 20.

In the form selected for illustrating this invention, blank 23 is comprised of a flat central section 32 and a conical tapered section 33, platen 11 being suitably formed to receive a blank so shaped. Blank 23 further is provided with an aperture 34 located centrally thereof, said aperture being of greater diameter initially than the central opening in the finished blank. It is contemplated that the central flat section 32 of the blank will be rolled and spun radially inwardly in the machine illustrated, to decrease the size of the central opening and to work the metal so rolled and spun to a denser and more homogeneous grain structure.

In order to assist in centering the blank on platen 11, said platen 11 is provided with a central opening 35 into which is adapted to be inserted a pin 36 extending downwardly from a conical disc 37. Said disc 37 is in turn connected to a piston rod 38 which is operated by a hydraulic cylinder 39 secured to plate 24 so as to be movable laterally therewith. Blank 23 will be approximately centered on platen 11 by virtue of the inherent centering effect produced by the conical portion 33 as it settles over platen 11. Final centering is accomplished by lowering conical plate 37 until it contacts the edges of aperture 34. Since pin 36 is accurately aligned with aperture 35, conical plate 37 will likewise be accurately aligned with platen 11 and, except for irregularities which might exist in the aperture 34, blank 23 will therefore be accurately centered upon platen 11. It is contemplated that plate 37 and its associated pin 36 will be raised completely from platen 11 and blank 23 during the rolling operation so as not to interfere with lateral movement of roll 22 across the surface of the blank.

It will be apparent thus far that unless blank 23 is securely clamped to platen 11 by a peripheral clamp, roll 22, as it moves across the blank, will tend to draw the blank over the surface of platen 11, thereby destroying the concentric relation between the platen and blank and rendering impossible the successful rolling-in of the central portion 32. Furthermore, should the blank become eccentric to the platen, large unbalanced forces will be developed which will tend to eject the spinning blank from the machine, thereby endangering the life of the operator. To avoid such a contingency, the novel apparatus hereinafter described is employed.

The required clamping action is obtained by means of a plurality of individual clamps 40 which are secured to the periphery of platen 11 at spaced intervals as shown in Fig. 2. Platen 11 is provided with pairs of lugs 41 which are apertured to receive a pin 42. Said pin passes through clamps 40 and provides a pivoted support therefor. Clamps 40 in turn are comprised of a depending mass 43 and an inwardly extending finger 44, the latter being designed to extend over the outer edge of blank 23. It is contemplated that finger 44 may have any desired shape and masses 43 likewise may be of any contour desired. As a feature of this invention, however, masses 43 and fingers 44 are so distributed with respect to pins 42 that when platen 11 is completely at rest, the center of gravity of mass 43

will tend to rotate the clamp in a manner to hold fingers 44 over the blank. To this end, masses 43 are largest immediately below pins 42 and at a point slightly removed radially inward with respect to pins 42. Since platen 11 is intended to be operated in a horizontal position, gravity will cause masses 43 to assume a position such that the center of gravity thereof will be below and radially inward of pins 42 and fingers 44, therefore, will be held over blank.

Thus it will be observed that clamps 40 are effective to prevent a blank 23 from leaving platen 11 even when said platen is not rotating and said clamps, therefore, are not entirely dependent upon centrifugal force for their effectiveness.

When in operation, that is to say, when platen 11 is rotating at operating speed, clamps 40 will develop sufficient centrifugal force by reason of the location of the center of gravity below pins 42 to hold blank 23 upon the platen despite any force which might be normally produced by roll 22 during its travel across blank 23. This centrifugal force of course increases with the square of the angular velocity and hence instead of decreasing the holding ability of the clamp, it increases the holding ability and renders perfectly safe the operation of the machine.

To assist in removing a blank from the platen, clamps 40 are rotated through an angle which is such that the edge 48 first passes upward through a slot 49 in platen 11 and engages the underside of the blank, and then raises the blank off the platen so that it can be gripped by a pair of tongs and removed. The raising is done in timed relation to the braking of the platen so that the blank is not free until it has stopped.

It is understood that the foregoing description is merely illustrative of a preferred embodiment of the invention and that the scope of the invention, therefore, is not to be limited thereto, but is to be determined by the appended claims.

1. claim:

1. A clamping device for holding a blank on a rotatable form, said form being adapted to rotate in a horizontal plane, said device comprising a plurality of weights, means for mounting said weights on the form for relative movement therewith, said mounting being adapted to permit the weights to move under the influence of centrifugal force, and mechanical clamping elements operated by the weights and adapted to hold a blank on the form, said elements being extended over the blank by the weights in the path of removal of the blank when the weights are at rest to prevent the blank from leaving the form inadvertently.

2. A clamping device as described in claim 1, and means for disengaging the elements operated by the weights from the blank to permit the blank to be removed from the form.

3. A clamping device for holding a blank on a rotatable form, said form being adapted to rotate in a horizontal plane, said device comprising a plurality of weights, means for mounting said weights on the form for relative movement therewith, means operated by the weights and adapted to hold a blank on the form, said mounting means being such that the force of gravity will be effective upon the weights to cause the holding means to prevent a blank from leaving the form when the form is not rotating, the force of gravity being supplanted by centrifugal force to clamp the blank to the form when the form is rotating, and external means operable upon the weights to counteract the force of gravity

when the blank is stationary, whereby to permit the removal of the blank from the form.

4. A clamping device for holding a blank on a rotatable form as described in claim 3, and means for intermittently starting and stopping the form, the external means being operable in timed relation with the means for stopping the form.

5. A clamping device as described in claim 3, a rotatable platform adapted to support the form and impart rotation thereto, and means for raising the form from the platform to arrest the rotation of the form, said external operating means for the weights being responsive to the raising movement of the form such that the external means is operative when the form is no longer driven.

6. A clamping device for holding a blank on a rotatable form, said device comprising a weight, means for pivotally supporting the weight from the form, said pivotal support being located eccentrically with respect to the center of gravity of the weight, a finger extending from the weight and adapted normally to extend over the blank and prevent it from leaving the form when the weight is not rotated, an extension on the weight, and external means adapted to engage the extension to rotate the weight and its associated finger away from the form, thereby to permit the removal of the blank from the form.

7. A clamping device for holding a blank on a rotatable form, said form being rotatable in a horizontal plane and having a conical surface thereon for supporting a blank, said device comprising a plurality of weights, pairs of apertured lugs extending from the periphery of the form and equidistantly spaced thereabout, pins passing through the apertures in the lugs and through the weights to provide a pivotal support for the weights, the center of gravity of the weights being below the pins, a finger extending radially inwardly from each of the weights over the conical portion of the form, said fingers normally being inclined over a blank when the form is at rest, a lateral extension on each weight, and means operating on the extensions to rotate the weights and their associated fingers in a manner to remove the fingers from the blank, thereby per-

mitting the blank to be withdrawn from the form.

8. A clamping device as described in claim 7, a rotatable platform adapted to support the form and impart rotation thereto, and means for raising the form from the platform to arrest the rotation of the form, said means operating on the extensions on the weights comprising a fixed abutment overlying the extensions and adapted to contact the extensions while the form is being raised.

9. A clamping device for holding a blank on a rotatable form, said device comprising a plurality of weights, means for movably mounting said weights on the form, said mounting means being adapted to permit the weights to move under the influence of centrifugal force, and mechanical clamping elements movable with the weights and adapted in one position to clamp the blank to the form, in another position to prevent the blank from leaving the form, and in a third position to support the blank over the form.

10. A clamping device for holding a blank on a rotatable form, said device comprising a plurality of weights, means for pivotally mounting said weights on the form, said pivotal mounting being eccentric to the center of gravity of the weights and being adapted to permit the weights to rotate under the influence of centrifugal force, means operated by the weights and adapted to clamp the blank to the form, said form having slots therein which are covered by the blank, and means likewise operated by the weights and adapted to pass through the slots to push the blank off the form when the form is not rotating.

11. A clamping device for holding a blank on a rotatable form, said device comprising a plurality of weights, means for mounting said weights on the form for relative movement therewith, said mounting means being adapted to permit the weights to move under the influence of centrifugal force, and mechanical clamping elements operated by the weights and adapted in one position of the weights to clamp the blank to the form and in another position to support the blank over the form.

DONALD H. CRAVENER, JR.
